MECHANISM FOR MAKING AND APPLYING
TRANSPARENT WINDOW PATCHES TO
ENVELOPES

Henry Kassekert, Maple Shade, N. J., and Frank J. Kaeser, Philadelphia, Pa., assignors to E. J. Spangler Company, Philadelphia, Pa., a corporation of Pennsylvania

Application January 14, 1933, Serial No. 651,756

5 Claims. (Cl. 93—61)

The present invention relates to a machine construction which may be regarded as an attachment or sub-mechanism which may be installed on and operated by and with envelope-making machines of different existing makes, and has for one of its objects, the replacement or substitution of the new patch-forming and applying mechanism herein disclosed for the patch-applying mechanisms which are usually used in machines for making envelopes with a window cut therein and a transparent strip of paper on the inside of the envelope covering the window.

A further object of this invention is to provide a patch-forming and applying mechanism in which the transparent patch material supplied thereto is in strip or ribbon form, a great length of which is wound on a reel or spool, the width of the strip of the ribbon being a little greater than the width (the short dimension) of the window in the envelope blank to provide an intermittently operating cutting mechanism which automatically severs substantially exact predetermined lengths of said patch material, the lengths of the severed pieces or patches being a little greater than the length (the longer dimension) of the window, and to immediately press the severed length of transparent material against the already applied stripes of glue surrounding, but spaced from, the edge of the window in the envelope blank.

A further object of this invention is to intermittently feed the web or ribbon of transparent window patch material longitudinally to a position over and in registration with the window opening in the envelope blank and immediately under a presser head or plunger, to then cut off an exact length of said material sufficient to amply extend beyond each end of the window opening and to then press the severed patch against gummed sides of the envelope blank, the gum having been applied to the blank just prior to the movement of the blank to the second or patch applying station.

A further object of this invention is to provide a machine in which a narrow strip of patch material is longitudinally moved into a position in which the free end of the strip is in registration with the window in an envelope blank, the ribbon being fed in a direction parallel to the length of the window and at right angles to the path of the movement of the blank through the envelope-machine as it is moved from the glue applying station, to a center station where

the blank dwells while the patch is applied to the blank.

A further object of this invention is to provide a patch-forming and applying mechanism which is operated in synchronism with the movement of the blank through the envelope-forming machine; which is simple in its construction; in which the various parts are readily accessible to the operator of the machine; in which the stock of material from which the patch is formed is at one side of the machine where it is accessible, instead of being as usual, midway between the sides of the machine; and in which all the various sub-mechanisms, which are brought into action, to feed the material, to sever it, and to press the severed patch against the envelope blank, are operated from a single control shaft lying substantially above the platen or table of the envelope-machine at the center stage or position of the blank therethrough and at right angles to the direction of the travel of the blank to and from said center position, said shaft being driven from the main driving shaft of the envelope machine to rotate in synchronism therewith.

Other objects will appear in the specification and claims below.

Referring now to the drawings forming a part of this specification and in which the same reference characters are employed throughout the various views to designate the same parts,

Fig. 1 is a diagrammatic view to illustrate the three successive operations which are performed on the blank of an envelope in its passage through the envelope-forming machine and with which this invention is adapted to cooperate in applying the patch of transparent paper to the window, the three stages comprising the first station wherein the gum is applied; the second station in which the patch is applied; and the third station wherein the envelope is folded;

Fig. 2 is an elevational view of my improved patch-forming and applying mechanism, the same extending over and transversely across the machine, being disposed at right angles to the travel of the envelope through the three stages of its progress above referred to;

Fig. 3 is a side elevational view of the mechanism shown in Fig. 2;

Figs. 4, 5, and 6 are fragmentary views of details of construction;

Fig. 7 is a plan view of the mechanism shown in Fig. 2 but on an enlarged scale to clearly illustrate the construction and operation of the attachment;

Fig. 8 is a side elevational view of my improved attachment looking from the front end of the envelope machine; that is to say, the opposite side of the mechanism illustrated in Fig. 2;

5 Fig. 9 is a fragmentary vertical cross-sectional view of the essential parts of the mechanism shown in Fig. 3;

10 Fig. 10 is a fragmentary plan view partly in section of the mechanism shown in Fig. 2 and Fig. 5 particularly showing the manner of driving the feed rolls and the way in which the attachment may be adjustably secured to the framework of the envelope-machine;

15 Fig. 11 is a side elevational view of the plunger for applying the transparent patch to the envelope blank;

Fig. 12 is a similar view of the opposite end of the mechanism shown in Fig. 8;

20 Fig. 13 is a fragmentary detail of construction showing the mechanism for intermittently rotating the feed rollers and for regulating the length of time that the rollers shall be rotated to feed forwardly the length of transparent window material sufficient to cover the window in the blank;

25 Fig. 14 is also a fragmentary sectional view of the mechanism operative to hold the envelope blank on the platen while the patch is being applied thereto; and

30 Fig. 15 is a side elevational view of the detail of the mechanism for actuating the knife or shears to sever the transparent window material to form a patch for application to the envelope blank.

35 In order that the nature of this invention may be made at once apparent, it should be here stated that there are existing envelope making machines which operate in what is usually referred to as three stages, positions or stations, 40 reference being had to the progress of the envelope blank through the envelope machine, and since this invention is particularly adaptable to operate with such machines, we will briefly describe those three stages or stations, as diagrammatically illustrated in Fig. 1.

45 The first stage or station is that in which the flat envelope blank 1 is given a stripe or line 2 of glue or other adhesive along the edges of the sealing flap 3, stripes 4 of adhesive along the 50 opposite edges of the opposite flap 5 and a stripe or stripes 6 of adhesive surrounding but spaced from the edges of the window opening 7 in the blank 1. This stage may be briefly referred to as the first or gum applying station.

55 Immediately the adhesive has thus been applied, the envelope blank 1 is bodily moved by a pair of carrier hooks 8-8 at the ends of the reciprocating carrier bars 9-9, or by any other suitable transferring mechanism, to the second 60 or center station wherein the motion of the blank is arrested. The blank stops or dwells in this station, in its travel through the machine and lies flat against the platen 10 and is held immovable with respect to the platen while the 65 carrier hooks are moved back away therefrom to the first position or station and while a second pair of carrier hooks 11-11 also carried by the bars 9-9 respectively, move to a position to the rear of the blank 1 thus held in the center 70 or second position or station.

75 While the blank 1 is thus held stationary with respect to the platen (by a mechanism to be referred to again below), a patch 12 of substantially transparent patch paper is brought into registration with the window is quickly pressed

down against the upper side of the blank and into contact with the stripes 6 of adhesive surrounding the window opening 7. The thin patch material adheres to the blank and the pressing plunger is immediately elevated or retracted and the patch is thus applied to the envelope blank.

80 As soon as this has been accomplished, the carrier bars 9-9 begin their forward movement, a new gummed blank being advanced by the hooks 8-8 to the center position, while the blank to which the patch is now attached is advanced to the third position or station in which the side flaps 13-13 are folded over down against the back of the rectangular portion 14 of the blank, the flap 5 is turned over to fold 15 down against the now upper sides of the flaps 13 and being pressed firmly against them causes the flap 5 to firmly adhere to the flaps 13.

85 During or just after the steps above enumerated the sealing flap 3 is also bent upwardly to 20 form the crease 15, but this flap is not pressed down against the back side of the now finished envelope because it would adhere thereto. The sealing flap 3 is merely bent upwardly and then the envelope so formed is delivered by any suitable mechanism to a drier, generally a chain driven carrier (not shown), in which the finished envelopes remain separate from each other for a length of time sufficient to allow the stripe 2 of adhesive on the sealing flap 3 to set and 30 harden.

90 So far we have described only those features of construction and operation which have been embodied in envelope-forming machines for a long time, the same being sufficiently descriptive of a three stage or station envelope-forming machine, for which our invention is particularly designed, to make it clear the manner in which the invention is to be installed on such machines to operate during a substantial dwell 40 of the blank on the flat support or platen 10 in the position above referred to as the "center" position or station which immediately follows the application of the glue to the blank.

95 The present invention provides a patch applying mechanism wherein a relatively narrow strip or ribbon 12' of transparent window material may be intermittently drawn from a spool or reel and fed intermittently longitudinally of the ribbon into position over the window opening 7 of an envelope blank and in a direction at right angles to the direction of the envelope through the envelope-forming machine and parallel to the long dimension of the opening and then severing an exact substantially constant 50 length of said ribbon to form a narrow patch 12 which is immediately automatically affixed to the envelope blank 1. In this respect this mode of utilizing a narrow ribbon 12' of substantially transparent material, the width of the ribbon being a little greater than the width (the short dimension) of the window opening 7, lends itself 60 particularly to three station envelope machines, to the simplification of the patch applying mechanism and by its use the patch may be severed and attached to the envelope with certainty (few misses) and accuracy (in registration).

100 In the accompanying drawings are shown only such parts of a standard envelope machine as are necessary to clearly set forth the construction and operation of a mechanism embodying the present invention, and for indicating the location of our improvement with respect to the standard parts of well-known envelope machine.

105 Referring now more particularly to Figs. 2 and 75

3, the envelope machine is shown as comprising a table 16 on legs 17, on which table is mounted the platen 10 on which the envelope is moved or slid from the gumming position to the patch applying station and from the patch applying station to the folding or final station. The platen 10 is supported on legs or supports 18. From the upper surface of the table 16 rise the usual arches or spans 19-20, the arch 19 being substantially at the gumming station and upon which the gum applying devices (not shown) are mounted and the arch 20 being located substantially at the folding station of the envelope machine for supporting parts of the folding mechanism (not shown). In order to install this invention on such an envelope machine, the two arches 19 and 20 are connected by two, preferably parallel horizontal rails or tracks 21, 22 rigidly secured thereto and extending longitudinally of the envelope machine, and on these rails we mount the frame 23 in or on which the essential parts of the present invention are carried. This frame 23 comprises a top plate 24 lying flat on the upper surfaces of the rails 21-22 and provided with a slot 25 (see Fig. 10) through which pass screws 26 threaded into hooks 27, engaging the undersides of the rails 21 and 22 respectively. By loosening the screws 26, the position of the top plate may be adjusted lengthwise of the slot 25 and longitudinally of the rails 21-22 to bring the operative mechanism carried by the frame 23 into proper position with respect to the envelope on the platen 10 of the envelope machine at the "center" station and when so adjusted the screws 26 are tightened and the top plate 24 and the parts carried thereby are held clamped rigid with respect to the framework of the machine. The frame 23 and the entire patch-forming and patch-applying mechanism, mounted therein is thus made adjustable in any direction in a horizontal plane so that the same may be readily adjusted to the position and sizes of different windows in different blanks. From the two ends of the top plate 24 depend the side plates 28 and 29 and the lower ends of said side plates are connected by and support a horizontal bottom plate 30 which extends transversely across the envelope machine. It is upon or within this frame 23 that the essential parts of the present invention are mounted. Thus, on the side of the top plate 24 is a bracket 31 extending upwardly and carrying a horizontal spindle 32 on which a spool or reel 33 of paper ribbon 12, which forms the supply of material from which the patch is to be made, is mounted to rotate freely on the spindle 32. On the rear side of said frame 23 and adjacent the bottom thereof are a pair of bearings 34 and 35 in which is mounted the main cam shaft 36 to extend horizontally transversely over the platen 10. On the left-hand side of the machine or frame 23, the shaft 36 extends outwardly and is further journaled in a bracket 37 provided with a channel 38 fitting over the edge of the table 16 and secured thereto by a set screw 39 passing through a slot 40 in the said bracket, so that the bracket may be adjusted longitudinally of the table to bring the journal of the shaft in that bracket into strict alinement with the bearings 34-35 on the frame 23. The end of the cam shaft 36 is provided with a sprocket wheel 41 driven by a sprocket chain 42 from a sprocket wheel 43 on the countershaft 44 in turn driven by a sprocket wheel 45 through a chain 46 from a sprocket wheel 47 fixed to the main drive shaft 48 of the envelope

machine. The sprocket wheels are preferably all of the same size and preferably have the same number of teeth so that the three shafts 36, 44 and 48 rotate in substantially absolute synchronism.

Referring now to Figs. 2, 3, 8 and 9, upon the outside of the plate 28 is mounted a bracket 49 in which is journaled a feed roller 50, fixed on its shaft 51. Also mounted on the bracket 49 is a frame 52, in the upper part of which is mounted a presser roller 53 normally held in yielding contact with the roller 50 by springs 54, one end of each being connected to the frame 52 and the other to the bracket 49. To hold the presser roller 53 separated from the feed roller 50, when desirable, there is mounted on the bracket 49 a bar 55, rectangular in cross-section, rotatable on its longitudinal axis and provided with a handle 56.

In the position shown in Fig. 9 the bar 55 is out of contact with the frame 52 and the spring 54 holds the roller 53 pressed against the roller 50. When, however, the handle 56 is lifted through 90°, the bar engages the frame 52, swings it about its pivotal axis, and separates the roller 53 from the roller 50.

The feed roller 50 is driven by a worm gear 58 on the end of the drive shaft 59 and meshing with a worm gear 60 on the vertical shaft 61 mounted in bearings 62, 63 supported on the side plate 28 and the lower end of the shaft 61 is provided with a beveled gear 64 meshing with a beveled gear 65 rigidly mounted on the cam shaft 36. Between the worm gear 60 and the feed roller 50 are a pair of friction clutch members 66, 67, the member 66 being rigid with respect to the worm gear 58 and the member 67 being slidable into and out of engagement with the member 66 and fixed to the shaft 51 of the roller 50 to rotate therewith. The clutch member 67 is normally held in frictional driving engagement with the member 66 by the spring 68 but it may be separated therefrom by the clutch separating member 69, which is a bell crank lever pivoted on a stud 70 also mounted on the bracket 49 and provided with a relatively stiff connecting rod 71 pivoted to the free arm of the bell crank lever 69 and having at its lower end 71' fitting an eccentric pin 72 on the end of the shaft 73 which is rotatably mounted in a pair of bracket arms 74-74, also on the face of the side plate 28.

The brackets 74 extend downwardly for a substantial distance and are respectively provided with a parallel slot 75 into which respectively fit the ends 76 of the roller 77 carried by and mounted to rotate in the ends of the links 78, the other ends of the links 78 being pivotally mounted on a bar 79 mounted in the lower ends of a pair of links 80, the upper ends of which are rigidly connected to the shaft 73. By reason of this construction any downward movement of the roller 77 in the slot 75 rotates the shaft 73 in a clockwise direction thereto throwing the eccentric pin 72 upwardly, moving the link 71 upwardly and, by rotating slightly the elbow lever 69, separates the clutch member 67 from the clutch member 66 to interrupt the rotation of the feed roller 50 and any upward movement of the roller 77 rotates the shaft 73 in the opposite direction turning the free end of the lever 69 toward the clutch member 66 and permitting the spring 68 to move the clutch member 67 into driving engagement with the clutch member 66 to recommence the driving of the feed roller 50.

Mounted on the main cam shaft 36 and rotatable therewith is a cylindrical cam 81 against the

cam edge 81' of which is held yieldingly pressed a roller follower 82 mounted at the lower end of a lever 83 mounted to swing on a stud 84 rigidly mounted in a bracket 85 extending upwardly from the bottom plate 30 of the frame 23. To the upper part of this lever 83, provided with a handle 83', is attached one end of a spring 86, the other end of which is connected to a pin or post 87 stationarily with respect to the bottom plate 30 (as on the bracket 122), the spring being operative to yieldingly hold the follower roller 82 against the edge 81' of the cam 81. The lever 83 is also provided with a pawl 88, the free end of which is normally held against the teeth 89' of a ratchet 89 by a spring 90, the ratchet 89 being freely rotatable on the stud shaft 84 and being rigidly connected with a gear 91 also freely rotatable on the stud shaft 84 and meshing with a pinion 92 rigidly mounted on the end of the shaft 93 suitably journaled in bearings 93' on the lower side of the bottom plate 30 and constituting the drive shaft of the lower feed roller 94. Cooperating with the roller 94 is the upper feed roller 95 suitably journaled in bearings 96' on the upper side of the bottom plate 30 on a shaft 96 provided with a gear 97 meshing with a gear 98 fixedly connected to the lower feed roller shaft 93 and with the pinion 92 so that the said rollers 94, 95 are geared and rotate at the same speed and are operative to draw between them the tape or ribbon 12' of patch paper as will be referred to again below. The pressure between the rollers 94 and 95 may be adjusted and controlled by any suitable device, as by the screws 95'.

Also mounted on the stud shaft 84 and adapted to be fixedly and adjustably secured thereto by the nut 99 is an arm 100 extending outwardly radially from the axis of the said stationary stud shaft and carrying on its free ends an arcuate shield or strip 101 lying close to and over the ratchet teeth 89'. This device is for the purpose of regulating and adjusting the number of teeth of the ratchet wheel 89 shall be advanced upon each complete rotation of the main cam shaft 36 or oscillation of the lever 83.

The gear 91 is provided with a brake drum or head 102 which is surrounded by an adjustable brake or friction band composed of two parts 103 and 104, the lower, 104, of which is rigidly secured to a post 105 and the upper, 103, of which is held yieldingly pressed toward the lower member by the springs 106 surrounding the screws 107 as is clearly shown in Fig. 8, the purpose of this friction mechanism being to prevent any overthrow or further movement of the ratchet wheel 89 and feed rolls 94-95 when the actuating mechanism therefor (lever 83 and pawl 88) comes to the limit of its forward movement and to thus insure the feeding of an exact substantially invariable length of patch ribbon or tape 12' for every complete rotation of the cam shaft 36. Mounted on the bottom plate 30 are channel bars 108-109 forming a guideway extending on both sides and in opposite direction from the line of contact between the upper and lower feed rollers 94 and 95 through which the ribbon of paper 12' from the spool or reel of paper 33 is advanced by the said feed rollers 94-95.

Next to the main cam shaft, 36 is a cam 109 rigidly secured to said shaft to rotate therewith, and coacting therewith is a lever 110 provided at its free end with a roller follower 111, said lever being pivotally mounted on a pivot pin 112 carried by a bracket 113 also rigidly mounted on the bottom plate 30. The lever 110 is provided with a

knife or shear blade which coacts with a stationary knife or shear blade 115 adjacent the discharge end of the guideway 108 and secured to the bottom plate 30. The knife blades or shears 114-115 extend directly across the path of the paper which is advanced through the guideway 108 by the feed rollers 94, 95 and it will be seen are operative to sever the paper tape or ribbon once after every revolution of the main cam shaft 36. A tension spring 110' is operative to hold the follower roller 111 against the surface of the cam 109, and a tension spring 114', connected to the free end of the blade 114 is operative to yieldingly hold the blade 114 against the stationary blade 115 and thus insures a clean severance of the paper thereby.

Immediately beyond the shearing blades 114-115, the bottom plate 30 is provided with a rectangular opening 116, the longer sides of which are provided with channel bars 117-117 in alignment with the guide bars 108-108 respectively and in which the severed pieces (patches 12) of patch paper 12' are supported just prior to the pressing of the same against the gummed envelope blank. The mechanism effecting this operation of the present device is particularly shown in Figs. 11 and 12 which show respectively the opposite sides of the same mechanism in elevation.

This mechanism is operated by a cam 118 fixed to the cam shaft 36 and coacting with a roller follower 119 carried at the end of a bar 120 mounted to slide longitudinally toward and away from the axis of the cam shaft 36 in a housing 121 rigidly secured to the side of a bracket 122 which in turn is rigidly secured to the bottom plate 30. Within the housing 121 the bar 120 is provided with rack teeth 120' in engagement with the teeth 123' of a pinion 123 rigidly mounted on a shaft 124 journaled in the bracket 122. On the other side of the bracket 122 the shaft 124 is provided with a segmental gear 125 meshing with the teeth 126' of a rack bar or plunger 126 mounted to slide vertically in a guideway 127, provided in the bracket 122. The lower end of this rack bar or plunger 126 is provided with a rectangular head 128 the dimensions of which are a little less than the dimension of the patch 12 to be applied. The upper end of the rack bar 126 is provided with a pin 129 to which is secured one end of a spiral spring 130, the other end being attached to a pin 131 on the outside of the guideway 127, the spring 130 being under tension and tending to move the rack bar downwardly and through the segmental rack 125 and rack and pinion 120-123 to hold the follower 119 against the cam 118 particularly as the follower traverses the low part 118' of the cam 118.

We have shown a piece of flexible tubing 132 attached to the upper side of the head 128 to indicate that the said head may be hollow and may be connected by the said tubing to an air pump or cylinder 133 mounted upon the table or frame 16 and pivotally mounted on a bracket 134 to oscillate, the air pump being provided with a piston rod 135 connected to a crank pin 136 mounted on the countershaft 44 and turned to exhaust air from the head 128 before the plunger 126 begins its downward travel and until the transparent patch has been affixed to the envelope blank and to break the vacuum in the head or presser 128 just prior to the time when the plunger 126 starts its upward movement. Such an air-pump attachment is contemplated by us whenever occasion demands the use of it,

but we have found that with a relatively stiff thin paper patch supported in the guide bars 117 spaced for only a short distance above the face of the blank, the suction device is unnecessary 5 and its use may be dispensed with. There are types of machines, however, in which it may be desirable to hold the patch firmly against the face of the head 128 in transferring the patch to the surface of the envelope blank, in which event, 10 the air-pump and connection to the hollow head 128 is preferred.

There is another sub-mechanism operable from the cam shaft 36 which will be next described. After the envelope blank 1 has been transferred 15 from the gumming position or station to the patch applying station, it must be held stationary with respect to the platen 10 during the patch applying operation to insure an accurate registration of the patch with the opening in the envelope. For this purpose there is mounted on the cam shaft 36 a cam 137 and there is rigidly mounted upon the bottom plate 30 a bracket 138 extending outwardly therefrom under the cam shaft and then upwardly above it. To the end 20 of this bracket 138 is pivoted a lever 139 having a roller 140 in engagement with the surface of the cam 137, and the lever 139 is preferably connected at its outer end with a vertical rod or plunger 141 mounted to slide vertically in a bearing 142 and below the bottom plate 30, the lower 25 end of said plunger 141 is provided with a head 143. A tension spring 144 is preferably attached at its ends to the bracket 138 and the lever 139 thereby being operative to hold the roller 140 in firm contact with the surface of the cam 137 and to depress the plunger 141 when the low part 30 of the cam 137 travels under the roller 140. This cam 137 is so timed or positioned on the cam shaft 36 that as soon as the carrier hooks on the 35 carrier bars 9-9 have brought the envelope blank to the center station, the plunger 141 descends so that any friction between the carrier bars 9-9 and the underside of the blank which may be present as the carrier bars return to the 40 front or feed end of the envelope machine sliding under the envelope blank, will not tend to displace or move in the slightest the envelope blank in that center position. It will be clamped and held firmly between the platen 10 and the 45 flat underside of the plunger head 143. It also follows that the position of the plunger 141 is, of course, one in which it is spaced from the edges of the opening 116 in the bottom plate 30 as clearly appears in the plan view of the mechanism in Fig. 7 and in Fig. 17.

In the envelope machine shown in the drawings as exemplified in Figs. 2 and 3, the main shaft 48 is continually driven and the sprocket wheel 43 is free to rotate on the countershaft 44 but is held from longitudinal movement on the countershaft by the collar 145. The sprocket wheel 45 is provided with a clutch member 146 rigid therewith and which cooperate with a sliding clutch member 147 which may be slid longitudinally on the countershaft 44, but is normally held pressed against the clutch member 146 by a spiral spring 148 between the clutch member 147 and a collar 149 stationary on the countershaft. The sliding clutch member 147 has a tongue, or 50 finger 150 which fits into a longitudinal groove 151 in the collar 149. The length of this finger 150 is such that it is never out of engagement with the groove 151 even when pressed to the left (see Fig. 2) to the limit of its motion in that 55 direction wherein it lies squarely against the

clutch member 146 on the sprocket wheel. The sliding member 147 is provided with an annular groove 152 in the surface thereof and the right-hand wall 152' of the groove 152 is provided with a cam 153.

Adjacent the right-hand wall 152' of the groove 152 is a cylindrical pin or rod 154 having a rounded nose or end 154' and this rod or pin 154 is slidable toward and away from the axis of the countershaft 44 in a suitable bearing 155 in 10 a bracket 156 depending from the table 16 of the envelope machine.

Connected to the pin 154 in any suitable manner, is a rod 157 which extends lengthwise of the envelope machine and terminates in a straight 15 horizontal section 158 passing through a bracket 159 depending from the table 16. The end of the rod 158 terminates in a knob 160 and between the framework of the machine and the collar 161 secured to the rod 158 is a spiral spring 20 162 under compression. Mounted on the bracket 159 is preferably a latch 163. The operation of this mechanism last described will now be apparent. The spring 162 normally holds the rounded end 154' of the rod 154 pressed toward 25 the axis of the shaft so that as soon as the cam 153 passes the end 154' of the rod, the spring forces the rod inwardly adjacent the vertical wall 152' of the groove 152 and as the shaft continues to revolve, the cam 153 sliding against the 30 end of the rigid pin or rod 154 moves the movable member 147 to the right (from the position shown in Fig. 2) disengaging the clutch member 147 from the clutch on the sprocket and rotation of the countershaft ceases. To start the countershaft the operator draws outwardly on the 35 knob 160 until the latch 163 takes against the rear side of the head or knob 160 and holds the rod 154 out of the groove 152. So long as the rod is retained in this position, the machine will be 40 continually driven from the countershaft. To stop the machine, the latch 163 is raised, the spring 162 forces the rod 157 to the left, crowds the end 154 into the groove 152 and separates the clutch member 147 from the clutch member 146. 45

To make ready to operate the machine, the end of the ribbon 12' of thin substantially transparent ribbon-like paper wound on the reel or spool, is passed down between the feed rollers 50 and 53, the presser roller 53 being held away from 50 the driven roller 50 by raising the handle 56 to the horizontal position, whereupon the rectangular bar 55 will force the lever upon which the roller 53 is mounted away from the roller 50 against the tension of the spring leaving a space 55 between the rollers. The web or ribbon 12' is then passed downwardly under the roller 77, and then upwardly into the guideway in and between the guide bars 108 secured to the bottom plate 30 of the frame and into and between the feed 60 rollers 94, 95 which may be rotated by oscillating the handle 83' when the follower 82 is opposite the low portion of the cam 81, to advance the end of the ribbon beyond the blade 114, 115 and into the guide bars 117, 117 in the opening 116. 65

When the envelope machine is operating and assuming the envelope blank to be on the platen 10 in the center or patch applying station, the feed rollers 95, 94 advance the ribbon or tape into and between the edges of the channel bars 117 70 on the sides of the opening 116 in the bottom plate 30 and beneath the head 128 of the plunger 126. As soon as the feed rollers cease rotating, (the follower 82 on the lever 83 having reached the low part of the cam 81), the knife blade 114 75

is now operated by the cam 109 to sever the patch roller 50 must feed or advance the web 12' a little faster than is required to supply the rollers 94, 95 and this roller 77 operates as a take-up in the following manner.

At substantially the time the envelope blank 1 comes to its dwell on the platen 10, the plunger 141 is operated by its cam 137 to hold the envelope blank immovable on the platen 10 in order that the carrier rods 9 may move rearwardly toward the front of the machine without changing the position of the blank on the platen.

At this point the cam 118 of the patch-applying mechanism has moved to a position wherein the lower member 118' of the cam begins its travel under the plunger bar 120, whereupon the plunger quickly descends carrying the severed patch held in the channel bars 117 downwardly on its face against the envelope blank and more specifically against the adhesive stripes 6 surrounding the window opening 1, and, having pressed the patch firmly against the blank, the plunger 126 quickly rises to the position shown in Fig. 11. In Fig. 12, the plunger is shown as having freed the patch from the channel bars 117 and as quickly transferring it to the blank on the platen.

In Figs. 11 and 12 the spacing between the plunger head or plate 128 and the patch 12 is exaggerated and the distance between the patch 12 and the platen 10 is exaggerated for the sake of clearness in illustration. The movement of the plunger 126 is relatively short and quick, the cam 118 is of a shape to permit the spring 130 to quickly depress the plunger and to as quickly restore it to its normal position shown in Fig. 11.

The patch having thus been quickly applied to the envelope blank and the plunger 126 having returned to its normal position, the continued rotation of the cam shaft and the cam 81 thereon has permitted the roller to reach the low portion of the said cam, the spring 86 holding the roller 82 against the surface of the cam and from that point the lower end of the lever 83 begins to move to the left (Fig. 2) causing the upward end of the lever to move clockwise, the pawl 88 sliding over the shield or plate 101 until it reaches the end of said plate, whereupon the pawl 88 comes into engagement with the teeth 89' of the ratchet 89 and the continued movement of the lever in a clockwise direction rotates the ratchet wheel 89 and with it the gear 91 to drive the feed rollers 94, 95 and advance the tape 12' a sufficient distance to form the next patch, which, at or upon the arrival of the next envelope blank to the patch applying station, is severed from the web 12' and pressed against the new envelope blank in the same manner as that heretofore described.

It is to be noted here that the feed or advance of the tape by the feed rollers 94, 95 is an intermittent motion and it is also to be noted that the rotation of the feed roller 50 coaxing with its presser roller 53 is normally continuous to continuously draw the ribbon 12' from the reel 33. During the period that the feed rollers 94, 95 are stationary or inoperative, the feed roller 50 normally continuously increases the length of the ribbon between the feed roller 50 and the intermittently operated feed rollers 94, 95. To insure that the feed roller 50 does not deliver the web 12' to the feed rollers 94, 95 substantially faster than it is utilized and advanced by the feed rollers 94, 95, the take-up roller 77 is employed to slide in the slots 75 vertically. The

When the rollers 94, 95 are stationary, the rod or roller 77 slowly descends gravitationally in the slots 75 as the web is continuously delivered or advanced by the feed roller 50. As it falls it slowly tends to straighten out the links 78, 80, turning the shaft 73 in a clockwise direction (Fig. 9). The eccentric pin 72 with which the shaft 73 is provided, is so positioned with respect to the shaft 73 that its direction is substantially vertically upward as the rod 77 falls or drops and this vertical movement of the eccentric pin 72 forces the connecting rod 71 slowly and slightly upwardly.

The upwardly movement of the connecting rod 71 (see Fig. 3) rotates the bell-crank lever 69 in a clockwise direction sliding the movable member 67 of the movable clutch member to the right against the tension of the spring 68 and away from the continuously rotating clutch member 66, with the result that the rotation of the feed roller 50 is stopped. When this takes place, and the feed rollers 94, 95 next quickly advance the tape the length of the patch, the rod 77 rises in the slot 75 and thus shortens the length of the material between the rollers 94, 95 and the now stationary feed roller 50 lifting the take-up roller 77. The upwardly movement of the roller 77, however, slowly rotates the shaft 73 (see Fig. 9) in an anticlockwise direction, moving the eccentric pin 72 downwardly or in an anticlockwise direction and allowing the spring 68 to push the sliding member 67 back into driving engagement with the clutch member 66, whereupon the feed of the web 12' from the reel 33 recommences. Thus it is that the position of the rod 77 controls the amount of ribbon or tape delivered to the intermittently operating feed rollers 94, 95, the feed roller 50 being driven from the continuous rotating clutch member 66 whenever the rod 77 is in its upward position and being disconnected from its driving relationship with the friction clutch member 66 whenever the rod 77 approaches its lowermost position in the slot 75.

By a correct adjustment of the arm 100 and with it the plate 101 with respect to the stationary stud shaft 84, the time when the pawl shall come into engagement with the ratchet teeth 89' can be accurately determined so that on every rotation of the cam 81 the ratchet 89 will be advanced a predetermined number of teeth and the forward end of the ribbon 12' will be advanced by the feed rollers 94, 95 from the edge of the blade 115 into and between the channel bars 117 to a predetermined position beyond the far end of the window opening 1 in the envelope blank held in the center or patch applying station. The length of material so advanced will be a little greater than the length of the opening 1 in the blank and a little longer than the long dimension of the rectangle 6 of glue on the envelope blank and the width of the tape or ribbon 12' is preferably somewhat greater than the width of the opening 1 in the blank and preferably slightly greater than the short dimension of the rectangle 6 of glue around the opening 1.

The dimensions of the rectangular head 128 of the plunger 126 are preferably a little less than the corresponding dimensions of the patch and preferably it is of substantially the dimen-

sions of the rectangle 6 of moist adhesive imprinted upon the blank, so that the adhesive is not squeezed outwardly beyond the marginal edges of the patch and the envelope under the pressure applied by the plunger 126, but lies all within the limits or boundaries of the edges of the patch, with the result that the envelope, with the patch freshly applied thereto, may be immediately advanced from the patch applying station to the folding station and there folded, and with the further result that the face 128 of the plunger 126 is always maintained clean, that is to say, without any adhesive on the face thereof.

Because of the construction heretofore referred to and wherein the patch 12 is supported in the guide bars 117 relatively close to the head 128 of the plunger 126 when the said plunger is in its normal elevated position and relatively close to the upper gummed surface of the envelope on the platen when it reaches the said center position, and because of the rapid operation of the plunger 126 in applying the patch to the blank, the patch 12 may generally be applied to the blank without the use of a vacuum for holding the patch immovable and firmly against the face of the patch applying plunger, but whenever there is any likelihood of the patch to move laterally out of registration with the window opening 7 as the patch is forced down from its channel-like supports 117 and is transferred thereover to the surface of the blank, or wherever the distance between the supports 117 and the platen is so great that the patch is likely to move transversely in its travel from its supports to the envelope blank, then the use of the pump 133 and the flexible tube 132 connected to the hollow head 128 is advisable.

From the foregoing the general sequence of steps and operations for which we have designed this machine will now be apparent and as follows: that as the blank is moving from the gumming station to the center or patch applying station the feed rollers 94 and 95 are operating to advance the paper into the channel bars or supports 117 so that the forward end of the ribbon 12' applied will be in its proper position over the blank at or about the time when its stops or dwells in said center station and that the feed rollers 94, 95 then stop; that the strip or ply or ribbon 12' is severed by the shears 114, 115; that immediately thereafter the plunger 126 will be actuated to descend and carry with it the severed patch 12 from the position above and in registration with the window or opening 7 in the blank, down into contact with the blank to which it adheres; that the plunger immediately rises and the blank, with the patch attached, is then advanced to the third or folding position, while the next gummed blank is brought into the center station, whereupon the operations of the mechanism as above referred to are repeated; and that the speed at which the web 12' is drawn from the reel is regulated, controlled or governed by a take-up mechanism mounted on the side of the frame and operable to automatically stop and start the operation of the drawing rollers 50, 53 by a take-up mechanism which operates by the variations which may occur in the length of the material between the drawing rollers 50, 53 and the main feed rollers 94, 95.

By feeding a ribbon or band of patch material into the machine transverse to the direction in which the envelope travels through the envelope

machine, the registration of the patch with the window in the blank can readily be effected by intermittently advancing the narrow ribbon lengthwise of the opening for an exact and predetermined distance and by mounting the reel or supply of material from which the patch is supplied on the side of the envelope machine, it is in a position of easy access. The mechanism for drawing the tape from the reel and for compensating for any variation in the rate at which the paper may be drawn from the reel is also convenient for access and adjustment. The whole patch mechanism is substantially mounted as a unit in or on the frame 23 and may be easily attached to and be used in connection with any envelope machine in which the envelope dwells in a fixed position after the gumming operation by suspending the frame and the parts mounted thereon from two rails attached to the upper framework of such envelope machines upon which rails the framework is adjustable to substantially any position with respect to the platen to adapt it to different types and sizes of envelopes and of windows therein. Moreover, the feed rollers, the knives, the patch applying plunger and the blank clamping plunger are all directly operated by cams, which can be set in timed relation, on a single shaft extending across the envelope machine, over the platen at the center station, where the timing of these sub-mechanisms can be accurately made and when any readjustment is necessary, as for a different envelope with a window of different size and location, the mechanisms are accessible from both sides of the machine for the operator to make such adjustments.

Having thus described our invention, what we claim and desire to protect by Letters Patent of the United States is:

1. In a patch-applying mechanism, the combination with a platen for an envelope blank having a window opening cut therein and adhesive freshly applied thereto around said opening, of a frame mounted to extend over and above said platen, a shaft mounted in said frame, means to support a roll of a ribbon of patch paper, the width of said ribbon being a little wider than the short dimension of said window, drawing means to normally draw said ribbon from said roll at a constant linear speed, a feed mechanism mounted in said frame and means driven by said shaft to intermittently rotate said mechanism to repeatedly advance, at each actuation thereof, a predetermined invariable length of said ribbon, said length being a little greater than the long dimension of said window in said blank, means to sever a patch from the free end of said ribbon after it has been advanced by said feed mechanism, stationary guideways mounted on said frame, in a fixed relationship with respect to said frame and engaging the opposite longitudinal sides of said ribbon to support the free end of said ribbon above the surface of said blank as it is advanced by said feed mechanism and to support said patch by its opposite longer side edges after severance from said ribbon, a patch-applying plunger mounted upon said frame and intermittently operated by said shaft to quickly force said severed patch downwardly, out from said guideway and to carry said patch to said envelope blank, over said opening and to press said patch into firm contact with said adhesive adjacent said opening.

2. In a patch-applying mechanism, the com-

bination with a platen for an envelope blank having a window opening cut therein and adhesive freshly applied thereto around said opening, of a frame mounted to extend over and above said platen, a shaft mounted in said frame, means to support a roll of a ribbon of patch paper, the width of said ribbon being a little wider than the short dimension of said window, drawing means to normally draw said ribbon from said roll at a constant linear speed, a feed mechanism mounted in said frame and means driven by said shaft to intermittently rotate said mechanism to repeatedly advance, at each actuation thereof, a predetermined invariable length of said ribbon, said length being a little greater than the long dimension of said window in said blank, means to sever a patch from the free end of said ribbon after it has been advanced by said feed mechanism, guideways in said frame and engaging the opposite longitudinal sides of said ribbon to support the free end of said ribbon above the surface of said blank as it is advanced by said feed mechanism and to support said patch by its opposite longer side edges after severance from said ribbon, a patch-applying plunger mounted upon said frame and intermittently operated by said shaft to transfer said severed patch from said guideway to said envelope blank, over said opening and into firm contact with said adhesive adjacent said opening, and means carried by said frame and actuated by said shaft to intermittently clamp said blank to said platen until said patch has been applied to said blank.

3. In a patch applying mechanism for window envelope machines comprising a platen to which the gummed envelope blanks are consecutively regularly fed, a rigid frame mounted over said platen, a main shaft mounted in said frame to continuously rotate in synchronism with said envelope machine, means mounted on said frame for supporting a supply of ribbon patch paper, a pair of coating feed rollers mounted on said frame, a mechanism mounted on said frame and driven by said shaft to intermittently rotate said feed rollers to advance between them a length of said ribbon a little longer than the long dimension of the opening in the envelope blank and to bring the forward end of said ribbon into registration with the opening in said blank on said platen, spaced guideways carried by said frame and in which the opposite edges of said ribbon slide immediately the ribbon leaves said feed rollers and by which the free end of said ribbon is supported above and parallel to said platen when said feed rollers intermittently stop, a mechanism mounted on said framework and intermittently operated by said shaft to sever the patch from the free end of said ribbon when said feed rollers have stopped and to leave said severed patch supported in said guideways at its side edges and in registration with said opening, an intermittently moving plunger mechanism mounted on said frame and operated by said shaft subsequent to the operation of said severing mechanism and provided with a plunger normally held stationary above the plane of said ribbon and in registration with said opening and movable vertically downwardly between said guides and operative when depressed to quickly detach said patch from said guiding means and to press it firmly against the gummed portion of said blank adjacent said window opening and to immediately thereafter elevate said plunger from said depressed position back to said position above the plane of said ribbon, a clamping mechanism mounted in said frame and operated by said shaft to hold said envelope blank immovable on said platen during the operation of said plunger mechanism, a pair of drawing rollers mounted in said frame and driven by said shaft and operative to normally continuously advance said ribbon at a rate slightly faster than the rate at which said ribbon is delivered by said intermittently operated feed rollers, to normally maintain between said feed rollers and said drawing rollers a loop of material of continually varying length, a take-up member floatingly mounted in said frame and supported by said loop, and means operated by said floating member to temporarily interrupt the

above the plane of said ribbon, a clamping mechanism mounted in said frame and operated by said shaft to hold said envelope blank immovable on said platen during the operation of said plunger mechanism, a pair of drawing rollers mounted in said frame and driven by said shaft and operative to normally continuously advance said ribbon at a rate slightly faster than the rate at which said ribbon is delivered by said intermittently operated feed rollers to normally maintain between said feed rollers and said drawing rollers a loop of material of continually varying length, a take-up member floatingly mounted in said frame and supported by said loop, and means operated by said floating member to temporarily interrupt the operation of said drawing rollers when the length of said loop is relatively long and to put said drawing rollers into operation when said loop is relatively short.

4. In a patch applying mechanism for window envelope machines comprising a platen to which the gummed envelope blanks are consecutively regularly fed, a rigid frame mounted over said platen, a main shaft mounted in said frame to continuously rotate in synchronism with said envelope machine, means mounted on said frame for supporting a supply of ribbon patch paper, a pair of coating feed rollers mounted on said frame, a mechanism mounted on said frame and driven by said shaft to intermittently rotate said feed rollers to advance between them a length of said ribbon a little longer than the long dimension of the opening in the envelope blank and to bring the forward end of said ribbon into registration with the opening in said blank on said platen, spaced guideways carried by said frame and in which the opposite edges of said ribbon slide immediately the ribbon leaves said feed rollers and by which the free end of said ribbon is supported above and parallel to said platen when said feed rollers intermittently stop, a mechanism mounted on said framework and intermittently operated by said shaft to sever the patch from the free end of said ribbon when said feed rollers have stopped and to leave said severed patch supported in said guideways at its side edges and in registration with said opening, an intermittently moving plunger mechanism mounted on said frame and operated by said shaft subsequent to the operation of said severing mechanism and provided with a plunger normally held stationary above the plane of said ribbon and in registration with said opening and movable vertically downwardly between said guides and operative when depressed to quickly detach said patch from said guiding means and to press it firmly against the gummed portion of said blank adjacent said window opening and to immediately thereafter elevate said plunger from said depressed position back to said position above the plane of said ribbon, a clamping mechanism mounted in said frame and operated by said shaft to hold said envelope blank immovable on said platen during the operation of said plunger mechanism, a pair of drawing rollers mounted in said frame and driven by said shaft and operative to normally continuously advance said ribbon at a rate slightly faster than the rate at which said ribbon is delivered by said intermittently operated feed rollers, to normally maintain between said feed rollers and said drawing rollers a loop of material of continually varying length, a take-up member floatingly mounted in said frame and supported by said loop, and means operated by said floating member to temporarily interrupt the

operation of said drawing rollers when the length of said loop is relatively long and to put said drawing rollers into operation when said loop is relatively short, the entire frame and the parts mounted thereon being adjustable as a whole in any direction in a plane parallel to said platen.

5. The combination with a window envelope machine having a framework and a platen, of a patch applying mechanism comprising in combination a frame, a drive shaft mounted therein and continuously rotated in synchronism with said envelope machine, a pair of coacting feed rollers mounted in said frame and driven by said shaft to advance between them a length of ribbon 10 a little longer than the long dimension of the opening in the envelope blank and to bring the forward end of said ribbon into registration with the opening in said blank, a pair of drawing rollers mounted in said frame and driven by said 15 shaft and operative to normally continuously advance said ribbon at a rate slightly faster than

the rate at which said ribbon is delivered by said intermittently operated feed rollers to normally maintain between said feed rollers and said drawing rollers a loop of material of continually varying length an intermittently operative cutting mechanism, an intermittently operative patch applying plunger and an intermittently operative mechanism to clamp the envelope blank to said platen, all said intermittently operating mechanism being mounted in said frame and operating in sequence from said drive shaft, the entire frame and the parts mounted therein being adjustable as a whole in any direction in a plane parallel to said platen, and means to immovably secure said frame to said framework with said patch applying plunger in registration with the window opening in the envelope blank on said platen.
